ELECTRODE FOR CHROMIUM PLATING

Lacey Glenn De Quasie and Robert E. Kochs,
Rochester, N. Y., assignors to Rochester Lead
Works, Inc., Rochester, N. Y., a corporation
of New York

Application September 26, 1951, Serial No. 248,348

5 Claims. (Cl. 204—286)

1

This invention relates to an electrode for use in chromium plating by electrolysis and has for its purpose to afford an anode that is economical to produce, efficient, durable, possesses good conductivity, is resistant to corrosion, and which overcomes the objections that have characterized previous types of anodes.

In the past, a type of anode that has been frequently used consists of a lead body portion which extends into the chromic acid bath and a hook portion of copper that is soldered or burned on to the lead body, and this type of construction has the objection that corrosion occurs at the meeting line between the copper hook portion and the lead body and such corrosion at the joint reduces the conductivity of the anode and also weakens the joint so that the hook portion is likely to break away from the body portion after being used for a time, and it is a particular purpose of the invention to overcome this difficulty by providing a structure in which the hook portion is formed integral with the lead-containing body portion so that there is no joint between the hook and body portions and consequently no likelihood of these parts breaking or separating from each other or of conductivity of the anode being reduced by corrosion at a joint between the hook and body portions.

Another type of anode that has come into use includes hook and body portions formed from an integral lead-containing bar or plate, and while this construction is satisfactory if the hook portion is constantly kept clean to afford good contact with the conductor bar, it is a further purpose of the invention to afford an anode including integral or one-piece lead-containing body and hook portions and to provide the hook portion with a copper element united to the hook portion in such a manner as to afford efficient and satisfactory contact with the conductor bar under all conditions and after continued use of the anode, resulting in greater conductivity, and to impart greater strength to the hook portion and lessen its chance of bending or straightening from the weight of the body portion of the anode.

An additional object of the invention is to afford a construction in which the hook portion is provided with a copper element for contact with the conductor bar and the copper surface protected in such a way as to avoid disintegration from chromic acid fumes of the bath and consequent mixing of copper particles with the bath which is undesirable because of resulting

2

contamination of the bath from the copper, and the present structure is such that while the copper element affords proper contact with the conductor bar and efficient conductivity, there is little likelihood of the bath being contaminated by copper disintegrating and loosening as a result of the chromic acid bath fumes attacking the copper at a point immediately above the surface of the bath.

To these and other ends, the invention consists in the construction and arrangement of parts that will appear clearly from the following description when read in conjunction with the accompanying drawings, the novel features being pointed out in the claims following the specification.

In the drawings:

Fig. 1 is a view in side elevation of an anode constructed in accordance with a preferred embodiment of the invention;

Fig. 2 is a rear elevation of the same;

Fig. 3 is a sectional view on line 3—3 of Fig. 1;

Fig. 4 is a sectional view on line 4—4 of Fig. 1, and

Fig. 5 is a transverse sectional view of the lead solder body that is used to unite the copper contact rod to the hook portion of the anode.

The invention is applicable in the manufacture of an anode formed of lead or lead combined with approximately 6% antimony or 4% to 7% tin or other strengthening and acid-resisting agent combined with the lead as in the manufacture of conventional lead anodes, and such a lead mass is first extruded to form a straight bar or plate including a body portion 1 which is preferably about $1\frac{1}{8}$ " thick from front to back at its outer edges, preferably about 3" in width and provided on its front surface with a central rib or flange 2 and outer ribs or flanges 3 spaced equally from the center rib and from the side edges of the body.

On its opposite or rear surface, the bar or plate is provided with a groove or recess 4 preferably of generally semi-cylindrical cross-section with a diameter of about $\frac{3}{8}$ ", extending longitudinally of the anode and centrally between the side edges for a purpose that will appear presently, and in order to impart adequate strength to the body and hook portions, the bar is somewhat thicker at the center adjacent to the groove or recess 4, as indicated at 5, and both the front and rear surfaces of the lead body taper outwardly toward the side edges where they are somewhat thinner, as indicated at 6. The bar or plate is cut away at opposite

sides at one end to afford a hook portion of reduced width, as well known in the art.

In order to afford a copper surface for contact with the conducting bar, a copper rod or other copper element of suitable cross-sectional shape is attached to the lead body before bending the latter to form the hook portion, the copper element being attached in such a manner as to afford an exposed contacting copper surface throughout the hook portion to a point on the body of the anode slightly above the normal level of the bath into which it is inserted, and in order to accomplish this, a semi-tubular body of lead solder, as indicated at 7, having an outer diameter the same as the diameter of the groove 4, is laid in the groove or recess 4, following which a cylindrical rod 8 of copper, having a diameter of about $\frac{1}{4}$ ", the same as the inner diameter of the semi-tubular solder body 7, is laid in the solder body. The solder employed for this purpose may consist of 40% tin and 60% lead or other suitable proportions, and while the rod 8 has been disclosed as cylindrical, it may be of any suitable cross-sectional shape as long as its exposed edge or surface affords satisfactory contact with the conducting bar.

After the parts are thus positioned, pressure is applied by clamps or in any suitable fashion to insure firm contact between the lead body, the solder body, and the copper rod, and heat is then applied to the copper rod 8 as by a blow-torch to melt the solder and bring about a firm rigid union between the copper rod 8 and the lead body. The heat thus applied is sufficient to melt the solder but not high enough to melt the lead of the lead body.

After the parts thus described are finally attached, the exposed surface of the copper rod 8 extends slightly above the adjacent surfaces of the solder body which hold it in the recess or groove, and thus insures a copper surface for contact with the conducting bar 9 on which the anode is supported. The copper rod 8 also performs the additional function of imparting increased strength to the hook portion of the anode, lessening any tendency for it to straighten from the weight of the body portion.

By extending the copper contact rod throughout the length of the hook portion, greater conductivity is assured and in order to protect the lower portion of the copper rod where it is located at a point slightly above the bath, the copper rod is preferably entirely covered by inserting over the outer portion of its lower end a semi-tubular portion of solder which is pressed against the copper rod and melted thereon to cover and protect the same as at 10, for a distance of about one inch, either at the same time that the inner solder member is united or subsequently thereto, as preferred. After the copper rod 8 is attached to the lead body of the anode, the latter is bent in a suitable fixture to form the hook portion 11 as usual in the manufacture of anodes.

An anode constructed in accordance with the invention has all the advantages and none of the objections of anodes in which a copper hook is burned on to a lead body, or anodes having integral lead body or hook portions in which a lead surface contacts with the conductor bar, and while the invention has been described in connection with a particular structure, it is not confined to the arrangement herein disclosed, and this application is intended to cover such modifications or changes as may come within

the purposes of the improvement and the scope of the following claims.

We claim:

1. A chromium plating anode comprising a one-piece body and a generally U-shaped hook portion containing at least a major proportion of lead, the hook portion having a groove extending longitudinally of its inner face coextensive with and arranged centrally between the side edges of the hook portion, and a copper contact rod located in said groove, said contact rod being coextensive endwise with the hook portion and having approximately one-half its cross-section embedded and secured throughout its length in said groove and approximately one-half its cross-section forming a continuous exposed surface coextensive with the hook portion and projecting laterally beyond the adjacent surfaces of the hook portion, said exposed surface of the copper contact rod having a tapering cross-sectional form affording a surface of limited area for contacting a conducting bar and said copper contact rod imparting increased stiffness and conductivity to said hook portion.

2. A chromium plating anode comprising a one-piece body and a generally U-shaped hook portion containing at least a major proportion of lead, the hook portion having a groove of semi-cylindrical cross-section of approximately $\frac{3}{8}$ " diameter extending longitudinally of its inner face coextensive with and arranged centrally between the side edges of the hook portion, a copper contact rod having a thickness of approximately $\frac{1}{4}$ " located in said groove, said copper contact rod being coextensive endwise with the hook portion and having approximately one-half its cross-section embedded and secured in said groove and approximately one-half its cross-section forming a continuous exposed surface coextensive with the hook portion and projecting laterally beyond the adjacent surfaces of the hook portion, and an elongated semi-tubular body of solder having a semi-cylindrical exterior surface engaging the aforesaid semi-cylindrical groove and arranged between said copper contact rod and the hook portion and uniting the copper rod to the hook portion throughout the length of the hook portion, said exposed surface of the copper contact rod having a tapering cross-sectional form affording a surface of limited area for contacting a conducting bar and said copper contact rod imparting increased stiffness and conductivity to said hook portion.

3. A chromium plating anode comprising a one-piece body and a generally U-shaped hook portion containing at least a major proportion of lead, the body and hook portions having a continuous rib extending endwise and centrally on the outer surface of the hook portion and on the front of the body portion, said body being thickest at its center adjacent to said central rib and tapered outwardly toward the side edges, the hook portion having a groove of semi-cylindrical cross-section of approximately $\frac{3}{8}$ " diameter extending longitudinally of its inner face arranged centrally between its side edges and coextensive endwise with the hook portion, and a copper contact rod having a thickness of approximately $\frac{1}{4}$ " located in said groove coextensive endwise therewith and attached throughout its length to the hook portion, said copper contact rod having a continuous exposed surface coextensive with the hook portion and projecting laterally beyond the adjacent surfaces of the hook portion, said ex-

posed surface of the copper contact rod having a tapering cross-sectional form affording a surface of limited area for contacting a conducting bar, and said copper contact rod imparting increased stiffness and conductivity to said hook portion.

4. A chromium plating anode comprising a one-piece body and a generally U-shaped hook portion containing at least a major proportion of lead, and a copper contact rod extending endwise of the hook portion on its inner face coextensive therewith and centrally thereof between its side edges and attached throughout its length to the hook portion, the copper rod being attached over approximately one-half its surface to the hook portion and approximately half the surface of said copper contact rod being exposed and projecting outwardly beyond the adjacent surfaces of the hook portion throughout the length of the hook portion and said exposed surface of the copper contact rod having a tapering cross-sectional form affording a surface of limited area for contacting a conducting bar, and said copper contact rod imparting increased stiffness and conductivity to said hook portion.

5. A chromium plating anode comprising a one-piece body and a generally U-shaped hook portion containing at least a major proportion of lead, the hook portion having a groove of semi-cylindrical cross-section of approximately $\frac{3}{8}$ " diameter on its inner face extending throughout the length of the hook portion centrally thereof

between its side edges, a copper contact rod having a thickness of approximately $\frac{1}{4}$ " located in said groove coextensive endwise with the hook portion, and an elongated semi-tubular body of solder partially surrounding said copper contact rod, the body of solder being coextensive with the hook portion and copper contact rod and securing the rod to the hook portion throughout its length and said copper rod having a continuous exposed surface coextensive with the hook portion projecting beyond the adjacent surfaces of the hook portion and solder and said exposed surface having a tapering cross-sectional form affording a surface of limited area for contacting a conducting bar, and said copper contact rod imparting increased stiffness and conductivity to said hook portion.
